JACK CONNECTOR FOR POWER TRANSMISSION LINES

George W. Miller, Sapulpa, Okla.

Application August 14, 1943, Serial No. 498,724

5 Claims. (Cl. 74—593)

1

This invention relates to a jack connection for use in a reciprocating power transmission line or the like to facilitate hook-up of the line with the actuating power after a break has occurred therein. For example, in multiple well pumping the pumping jacks are actuated through transmission lines usually composed of strings of rods radiating from a central power. Such rods operate under severe load conditions and it is common for the rods to break. When these breaks occur the broken end separates by reason that the weight of the sucker rods and fluid being lifted is acting upon the pumping jack and it is necessary to reengage the transmission line with the power under such weight after the repair has been made. This is a difficult procedure because after the repair, the coupling members have separated a distance corresponding to the distance that the line separated, and consequently the weight acting on the pumping jack must be lifted before the gap between the coupling members is closed.

It is, therefore, a principal object of the invention to provide a power transmission line with a jack connection which, in the case of a break, may be let out at the time of the repair so that the line may be readily coupled with the power and the slack drawn up under load incidental to actuation of the power.

Other objects of the invention are to provide a connector of this character that is of simple construction, positive in operation, and which may be manipulated with a minimum of effort on the part of the operator.

Further objects of the invention are to provide a jack connection that may be used in hooking the rods on and off the power and which holds the rods in hook-off position; and to provide a connecting jack mechanism which serves as a rod guide.

In accomplishing these and other objects of the invention, as hereinafter described, I have provided improved structure, the preferred form of which is illustrated in the accompanying drawings, wherein:

Fig. 1 is a perspective view of the portion of a transmission line including the hook-on and hook-off coupling members and illustrating the improved jack connection applied thereto, the hold-up post being shown in dotted lines.

Fig. 2 is a plan view of the parts illustrated in Fig. 1 with the guide housing of the connecting jack shown in section to better illustrate engagement between the bar members that are slidably therein.

2

Fig. 3 is a side elevational view of the parts shown in Fig. 1 also with the guide housing in section.

Fig. 4 is a view similar to Fig. 2 but showing the bar members in distended position preparatory to drawing up the line after a break has been repaired and the hook-off coupling has been reengaged.

Fig. 5 is a perspective view of one of the bar members.

Fig. 6 is an enlarged section on the line 6—6 of Fig. 1.

Referring more in detail to the drawings:

1 designates a transmission line comprising a string of rods such as connect a central power (not shown) with a well pumping jack (also not shown). The power usually comprises a band wheel having an eccentric to which one end of the string of rods is connected, the other end of 15 the string being connected with a rocker arm of the pumping jack whereby the string of rods is reciprocated to effect oscillation of the pumping jack incidental to rotation of the band wheel.

Interposed in the string of rods, preferably 20 near the power, is a "hook-on and off" coupling mechanism which usually includes a hook 2, pivotally connected with one section 3 of the string of rods, and a link 4 that is connected with the other section 5 as illustrated in Fig. 20. Located back of the link 4 and in the direction of the well being pumped is a hold-up post 6 having an opening 7 through which the rods ordinarily extend for supporting the link 4 in position to be engaged by the hook. The structure thus far described is conventional and specifically forms no part of the present invention.

Due to the fact that the string of rods is in 25 continuous motion and subject to severe load tension, it is subject to breakage with the result that the pump or sucker rods drop to the bottom of the well under weight of the well fluid being lifted which causes separation of the broken ends of the rods and disengagement of the hook 2 from the link 4. After the rods have been repaired the hook 2 will not reach the position of the link 4 so that it may be readily reengaged therewith.

It is, therefore, a principal object of the present invention to provide a jack mechanism for connection in the string of rods and which may be extended so that after repair is made the link 4 is in position to be readily engaged by the hook 2 and the jack connection is drawn up automatically incidental to reciprocation of the rods

under action of the power. This mechanism includes a pair of bar-like members 8 and 9, the bar 8 being connected with the link 4 by a suitable connector 10 while the other bar is connected with the section 5 of the rods through a similar connector 11. The free ends 12 and 13 of the bars overlap in side to side relation and are slidably supported within a guide housing 14.

The guide housing includes a top 15 having depending sides 16 and 17 spaced apart to accommodate the bars 8 and 9 therebetween and provide sufficient space as indicated at 18 to permit lateral movement between the bar members as later described. The side wall 16 has a rib or flange portion extending inwardly in the direction of the opposite side 17 to support a wear plate 19 that is suitably attached to the guide housing and which extends along the length thereof as shown in Fig. 4. The upper surface 20 of the wear plate is spaced from the top 15 of the housing a sufficient distance to allow free sliding movement of the bar member 8 therebetween and the edge 21 thereof is spaced from the wall 17 to accommodate toothed portions 22 depending from the lower edge of the bar 9. The bar members are ordinarily connected by interengaging means comprising a series of spaced teeth 23 on the bar member 9 engaging in notches 24 of the bar member 8. The teeth 23 preferably have shoulder portions 25 on the sides thereof in the direction of the well and inclined faces 26 in the direction of the power. The notches 24 preferably conform to the shape of the teeth so that when engaged therewith a rigid driving connection is provided therebetween. In order to retain the bars in lapping engagement with the teeth received in the notches, the ends of the bars are secured together by fastening devices, such as screws 27, extending through suitable openings 28 in the bar 8 and into threaded openings 29 in the bar 9 (see Fig. 2).

The tooth portions on the lower edge of the bar 9 include a series of stop shoulders 30 facing in the direction of the well and have lower edges 31 sloping upwardly toward the base portion of the next adjacent shoulder as best illustrated in Fig. 5.

Mounted transversely within the guide housing at a point below the bar members is a shaft 32 carrying a cam-like pawl 33 operable between the sides 16 and 17 and having a portion 34 adapted to engage the under edge of the bar member 8 for lifting the bar into clamping contact with the top of the housing. The portion 34 is also shaped to provide a toe 35 for engaging the shoulders 30 to retain the bar members in fixed relation with respect to the guide so as to facilitate disengagement of the hook 2 from the link 4 when it is desired to suspend operation of the well being pumped and to effect taking up of slack in the rods after a repair has been made, as later described. One end of the shaft 32 projects through the side wall 17 of the guide and carries a crank arm 36 by which the shaft may be oscillated to actuate the cam. The guide member is attached to the post 6 by means of straps 37 and 38 having ends secured to opposite sides of the posts by suitable fastening devices as indicated at 39, while the opposite ends are attached to the sides 16 and 17 of the guide member by similar fastening devices 40.

In operation, the interconnected bar members reciprocate through the guide housing 15 in sliding support on the wear plate 19 as long as the hook 2 is engaged with the link 4. During nor-

mal operation, the shaft 32 is moved so that the cam 33 is in retractive position as shown in Fig. 2. However, when it is desired to disconnect the hook 2 from the link 4, the crank 36 is operated to move the toe of the cam into position to be engaged by one of the shoulders on the bar 9 for stopping movement of the rods on the down stroke of the pump jack. The cam then supports the load acting upon the jack and the hook 2 will be released sufficiently to drop from the link, leaving the link in position to permit reengagement of the hook therewith when it is again desired to pump the well.

To reengage the link 4, it is only necessary to swing the hook 2 into engagement therewith when the sections of the rods 3 are moving in the direction of the well being pumped. The cam is then disengaged from the bar 9 whereupon the load carried by the jack is transferred to the hook.

In case the string of rods should break while in operation, the sucker rods in the well will drop to their lowermost position and cause the pump jack to draw the ends of the break apart. Consequently the hook 2 will drop from the link 4 and automatically disconnect the power.

To repair the break the fastening devices 27 will be removed from the bars 8 and 9 so that the bars may be separated to disengage the teeth 24 of the bar 9 from the notches of the bar 8. The bars may then be drawn apart longitudinally to extend the effective length of the string of rods and leave the link 4 in such as position that it is readily engaged with the hook 2 after the break has been repaired.

After the repair, the link 4 is reengaged with the hook 2 and manually held in engagement therewith. The cam 33 is then brought into engagement with the lower edge of the bar 9 with sufficient pressure so that the upper edge of the bar is moved into clamping engagement with the top 15 of the guide housing. The bar 9 is thus retained in immobile position while the hook engaged with the link 4 moves the bar 8 through the guide until the end of the stroke is reached, whereupon the bar 8 is manually moved laterally so that the notches therein engage the teeth 23 of the bar 9. Then upon the retractive stroke, pressure on the cam is released so that the power acts to lift the sucker rods in the well through tooth engagement of the bar members. At the end of the reverse stroke the cam is again engaged with the bar 9 to stop movement thereof and to support the load thereon. On the next stroke the bar 8 again moves through the guide to advance its engagement with the teeth of the bar 9. At the end of this stroke lateral pressure by band will cause the notches to reengage the teeth and when the direction is reversed the load is again picked up. These operations are repeated until the openings 23 in the bar 8 register with the openings 29 in the bar 9, whereupon the screws are re-inserted to draw the bars together and retain the teeth in engagement with the notches.

It is thus obvious that after a break, the link 4 may be readily engaged with the hook 2 upon letting out of the bar members 8 and 9 and that the resulting slack is readily taken up incidental to actuation of the central power. It is also obvious that the jack connection may be used in hooking on and off of the line when suspending or starting operation of the pump jack operated thereby, and the jack connection supports the

rods against the load on the pump jack when the pumping operation is suspended.

What I claim and desire to secure by Letters Patent is:

1. A device of the character described including, a guide having laterally spaced sides and interconnected at the top thereof, a pair of members having reciprocating support by the guide, means carried by the guide to hold one of the members in fixed position relatively to the guide when the other is moved in one direction through the guide, interengaging means on said members, said interengaging means being manually engageable to effect movement of the members in the guide upon reverse movement of said other member, and means connecting said members together whereby said members reciprocate as a unit. 15

2. A device of the character described including, a guide having laterally spaced sides and interconnected at the top thereof, a pair of members having reciprocating support in the guide, one of said members having teeth on the edge thereof, means carried by the guide for engaging said teeth and to move said member in clamping engagement with the guide when the other member is moved in one direction through the guide, and interengaging means between the members, said interengaging means being manually engageable to effect movement of the members in the guide upon reverse movement of said other member, said interengaging means including teeth on one of the members engaging notches in the other member. 25

3. A device of the character described including, a guide having a top and depending sides, a pair of reciprocable bar members adapted to be connected in a string of rods, a wear plate carried by one of the sides for supporting one of said pair of reciprocable bar members, said guide being of sufficient width to provide a space between one of its sides and said bar member carried by the wear plate, means for frictionally selectively retaining the other bar member in fixed relation with the guide while the first bar member is reciprocated in one direction on said plate in said space, and interengaging means between the bar members, said interengaging means being manually engageable for effecting movement of both bar members in the guide upon reverse movement of said other bar member. 35

4. A device of the character described including, a guide having laterally spaced interconnected sides, a pair of reciprocable bar members adapted to be connected in a string of rods, means carried by one of the sides for supporting one of said pair of reciprocable bar members, cam means for supporting the other bar member and for moving said other bar member into clamping engagement with the guide when the first bar member is reciprocated in one direction, and interengaging means between the bar members, said interengaging means being manually engageable for effecting movement of both bar members in the guide upon reverse movement of said first bar member. 10

5. A device of the character described including, a guide having laterally spaced interconnected sides, a pair of reciprocable bar members adapted to be connected in a string of rods, means carried by one of the sides for supporting one of said pair of reciprocable bar members, cam means for supporting the other bar member and for moving said other bar member into clamping engagement with the guide when the first bar member is reciprocated in one direction, interengaging means between the bar members, said interengaging means being manually engageable for effecting movement of both bar members in the guide upon reverse movement of said first bar member, and fastening devices for connecting said bar members to reciprocate as a unit. 20
